UNITED STATES PATENT OFFICE

2,508,177

DUAL PURPOSE CHAIR

Norman Levine, New York, N. Y.

Application August 3, 1946, Serial No. 688,371

5 Claims. (Cl. 155—41)

1

This invention relates to household furnishings and more particularly to chairs especially adapted for bedroom use wherein it is desired to have at times a back support for use in a bed as at times of reading or when one is convalescing.

It is an object of the present invention to provide a bedroom chair which has a dual purpose and wherein the top part including the arms and back support may be removed from the seat and chair base and used in a bed for a back support.

It is another object of the invention to provide an easy means for the connection of a chair top to its base which permits easy removal of the chair top so as to make it easily and readily accessible for bed use.

It is another object of the present invention to provide a removable chair top with means for connecting the same to its base so that it can be connected or removed without difficulty.

According to the invention, an upholstered bed rest is provided from a chair top. The chair top is so connected to the chair seat or base that it can be easily removed from the chair base at times when it is desired to use the chair top as a bed rest. On the top of the seat there is provided a U-shaped retaining guide having two sides and an inclined rear portion.

The forward end of each of the two sides are spaced from one another and have downwardly and rearwardly inclined end faces for preventing, when cooperating with internal downwardly and rearwardly inclined faces in the arms of the chair, any rearward tilt of the chair top relative to the chair seat whereby the chair top is held rigidly in place on the chair seat. A latch connects the back of the chair top with the inclined rear portion of the U-shaped member to hold the same in place against forward tilting except at times when it is desired to remove the chair top from the seat. The bottom face of the chair top has a U-shaped slot for receiving the U-shaped member and hence is smooth and free of any projections which might tear the bed clothing when the chair top is used in the bed as a bed rest. The back of the chair top is indented or shaped to accommodate the inclined rear portion of the U-shaped member. The amount of inclination of the rear portion of the U-shaped member is less than the inclination of the forward ends of the side portions thereof and only such as to facilitate the placing of the chair top upon the U-shaped member. The top rear edge of the rear portion is accordingly relieved.

2

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of the combined chair top and chair seat, the chair top being in place on the chair seat and the chair made ready for use.

Fig. 2 is a side view of the combined unit shown in Fig. 1.

Fig. 3 is a front elevational view of the same.

Fig. 4 is a perspective view of the chair seat alone with the chair top having been removed and showing the upstanding U-shaped guiding and retaining projection for the chair top.

Fig. 5 is a perspective view of the chair top removed from the seat.

Fig. 6 is a bottom perspective view of the chair top.

Fig. 7 is a side elevational view of the chair seat and of the chair top illustrating the first stages of positioning the chair top upon the chair seat.

Fig. 8 is an enlarged fragmentary rear view of the combined chair top and seat and showing the location of the latch device.

Fig. 9 is an enlarged cross-sectional view taken through the combined top and seat along the line 9—9 of Fig. 3 and in the region of the latch device.

Fig. 10 is a fragmentary cross-sectional view taken along the line 10—10 of Fig. 9, looking in plan upon the latch device.

Fig. 11 is a detail perspective view of the latch element removed from the chair top.

Fig. 12 is a rear perspective view of the retaining plate for the latch device serving to hold the same in pivoted relationship on the back of the chair top.

Referring now to the figures, the combined chair top and seat is indicated generally at 21 and comprises a chair seat 22 and a chair top 23. The chair seat 22 has a top seating surface 24 with a U-shaped retaining and guiding projection 25 extending upwardly therefrom. This projection 25 has side portions 26 and a slightly forwardly inclined rear portion 27 connected between the side portions at the rear of the seat. The side portions 26 are parallel to one another and have pointed forward ends 28 formed by providing a downwardly and rearwardly inclined

face 29 thereon. The inclination of the rear portion 27 is only slight and considerably less than the inclination of face 29 though extending in the same direction.

The chair top 23 is of U-shaped configuration and has arm portions 31 and a raised back 32. In the bottom of the chair top is a U-shaped recess 33 conforming to and adapted to receive the U-shaped projection 25 of the chair seat, Fig. 6. The forward ends of the recess 33 have a downwardly inclined surface 34 adapted to engage the surface 29 of the projection 25 so that when the chair top is down upon the seat rearward tilt of the chair top is prohibited. Upon engaging the chair top over the projection, the inclined faces 34 of the chair top recess 33 are first engaged with the surfaces 29 on the front ends of the side portions 26 of the projection 25 and then the chair top is pushed backwardly and downwardly into place so that the recess receives the inclined rear portion 27 of the projection 25, Fig. 7.

The lower portion of the seat back 32 is depressed to allow the recess 33 to be inclined at the rear to accommodate the inclined rear portion 27 of the U-shaped projection, Fig. 9.

In the rear portion 27 of the projection 25 there is a slot 35 midway across the portion 27 Fig. 10. This slot 35 is adapted to receive a securing lug 36 on a pivoted latch 37 lying within a recess 38 in the back of the chair top, Fig. 10. This latch 37 has trunnions 39 adapted to fit in half-circular sockets 41 at opposite sides of the recess. In order to locate the latch 37 within the recess and to place the trunnions 39 in their sockets 41, there is a removable plate 42 adapted to be taken from the rear of the seat, Fig. 12. Once the latch has been dropped down into the recess 38, the plate 42 is secured in place by screws extending through holes 43 at opposite sides of the plate. Upon the inner face of the plate 42 are projections 44 and 45 having half-circular sockets 46 aligned with the half-circular sockets 41 and adapted to fit over half of the trunnions 39 so as to complete the journal connection of the trunnions with the back of the chair top.

In order to urge the lug 36 on the latch into the slot 35, there is provided a leaf spring 47 on the rear face of the latch adapted to cooperate with the rear inner face of the removable plate 42. On the upper end of the latch 37 there is a button projection 48 adapted to extend through a hole 49 in the removable plate 42. When it is desired to release the chair top from the projection, the button 48 is depressed against the action of the leaf spring 47 to disengage the lug 36 from the slot 35.

This chair top is made on its bottom edge to be smooth so that it can be safely located on a bed when removed from the chair seat and used as a bed rest. The rear part is preferably upholstered but the arms and the bottom may be made of metal or plastic. The latch is well confined within the recess 33 so as not to hinder the use of the rest upon the bed. The recess 33 is of such size as to easily accommodate the projection 25. By being inclined at the rear the removal and insertion of the chair top is facilitated.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A chair of a type having a removable chair top adapted for use as a bed rest when removed from a chair seat comprising a chair seat having a projection extending from the seat surface thereof, a chair top having a recess in the bottom conforming to the shape of the projection on the chair seat, releasable means for securing the chair top when in place upon the seat projection, said chair top being adapted when removed from the chair seat to serve as a bed rest, said seat projection being U-shaped and having side portions and a rear portion, the forward ends of said side portions of the projection having a downwardly and rearwardly inclined engaging edge, the portions of the recess within the chair top having an inclined face adapted for retaining engagement with the inclined edge of the projection, whereby the chair top when fixed in place upon the seat is automatically retained against rearward tilting movement with respect thereto.

2. A chair of a type having a removable chair top adapted for use as a bed rest when removed from a chair seat comprising a chair seat having a projection extending from the seat surface thereof, a chair top having a recess in the bottom conforming to the shape of the projection on the chair seat, releasable means for securing the chair top when in place upon the seat projection, said chair top being adapted when removed from the chair seat to serve as a bed rest, said seat projection being U-shaped and having side portions and a rear portion, the forward ends of said side portions of the projection having a downwardly and rearwardly inclined engaging edge, the portions of the recess within the chair top having an inclined face adapted for retaining engagement with the inclined edge of the projection, whereby the chair top when fixed in place upon the seat is automatically retained against rearward tilting movement with respect thereto, and said releasable means including a latch confined within the rear portion of the top recess vertically removed from the bottom face of the chair top and adapted to engage with the rear portion of the seat projection to retain the chair top against forward tilting movement when the chair top is in flush engagement with the chair seat.

3. A chair of a type having a removable chair top adapted for use as a bed rest when removed from a chair seat comprising a chair seat having a projection extending from the seat surface thereof, a chair top having a recess in the bottom conforming to the shape of the projection on the chair seat, releasable means for securing the chair top when in place upon the seat projection, said chair top being adapted when removed from the chair seat to serve as a bed rest, said seat projection being U-shaped and having side portions and a rear portion, the forward ends of said side portions of the projection having a downwardly and rearwardly inclined engaging edge, the portions of the recess within the chair top having an inclined face adapted for retaining engagement with the inclined edge of the projection, whereby the chair top when fixed in place upon the seat is automatically retained against rearward tilting movement with respect thereto, and the rear portion of the seat projection slightly inclined forwardly and an amount substantially less than the inclination of the engaging edges of the side portions where-

by to facilitate the attachment and detachment of the chair top with the seat projection.

4. A chair of a type having a removable chair top adapted for use as a bed rest when removed from a chair seat comprising a chair seat having a projection extending from the seat surface thereof, a chair top having a recess in the bottom conforming to the shape of the projection on the chair seat, releasable means for securing the chair top when in place upon the seat projection, said chair top being adapted when removed from the chair seat to serve as a bed rest, said seat projection being U-shaped and having side portions and a rear portion, the forward ends of said side portions of the projection having a downwardly and rearwardly inclined engaging edge, the portions of the recess within the chair top having an inclined face adapted for retaining engagement with the inclined edge of the projection, whereby the chair top when fixed in place upon the seat is automatically retained against rearward tilting movement with respect thereto, and the rear portion of the seat projection slightly inclined forwardly and an amount substantially less than the inclination of the engaging edges of the side portions whereby to facilitate the attachment and detachment of the chair top with the seat projection, and said chair top having its lower portion depressed to permit the rear portion of the recess to be inclined to accommodate the inclined rear portion of the projection.

5. A chair comprising a base having a top seat portion, a projection formed on said top seat portion and having forwardly extending portions projected along the sides of said seat portion, and a chair top comprising a back and forwardly extending side arms formed in its bottom face with a recess into which said projection engages, said forwardly extending portions of said projection having their front ends inclined forwardly and upwardly and engageable with complementary walls defining portions of the recesses in said chair top whereby rearward pressures against the back of said chair top will cause said complementary walls of said chair top to slide downwards on the forwardly and upwardly inclined ends of said forwardly extending portion of said projections and securely hold said chair top in position on said base.
